CHARLES H. DAVIS.

UNITED STATES PATENT OFFICE.

CHARLES H. DAVIS, OF WORCESTER, MASSACHUSETTS.

DENTAL PLUGGER.

SPECIFICATION forming part of Letters Patent No. 639,536, dated December 19, 1899.

Application filed July 29, 1899. Serial No. 725,547. (No model.)

To all whom it may concern:

Be it known that I, CHARLES H. DAVIS, a citizen of the United States, residing at Worcester, in the county of Worcester and 5 Commonwealth of Massachusetts, have invented a new and useful Improvement in Dental Pluggers, of which the following is a specification, accompanied by drawings forming a part of the same, and in which—

10 Figure 1 represents a side elevation of a dental plugger embodying my invention. Fig. 2 is a central longitudinal sectional view. Fig. 3 represents a detached view of a tool-holder shown partly in sectional view and 15 containing a plugging-tool adapted to impart a blow by a direct forward movement, a portion of the tool-holder being shown in sectional view in order to disclose the mortise therein and the beveled-faced actuating-spindle. Fig. 4 is a side elevation of the tool 20 and tool-holder shown in Fig. 3. Fig. 5 is a view of the sliding ring and elastic blade by which the screw-threaded collar on which the rotating head is mounted is held from 25 turning. Fig. 6 represents the tool-holder carrying a plugging-tool adapted to impart a blow on its reverse or backward motion, and Fig. 7 represents a screw-threaded collar upon which the rotating head is mounted.

30 Similar letters refer to similar parts in the different views.

The object of my present invention is to provide a mechanism for actuating a plugging-tool in that class of dental pluggers in 35 which the plugging-tool is arranged to be operated at an angle to the direction of the movement of the reciprocating blow-imparting plunger, whereby the same actuating mechanism will serve to impart a blow to the 40 plugging-tool upon its forward stroke when plugging-tools of the kind shown in Fig. 3 are employed and also to impart a blow to the plugging-tool upon its reverse stroke when curved or bent plugging-tools are employed 45 like that shown in Fig. 6, without requiring any change in the actuating mechanism, thereby enabling blows to be imparted to the plugging-tool upon either its forward or backward stroke as either a straight or curved 50 plugging-tool is used. I accomplish these objects by means of the mechanism shown in

the accompanying drawings and hereinafter described; and my invention consists in the novel construction and arrangement of the operating parts as pointed out in the annexed 55 claims.

In the accompanying drawings I have represented an actuating mechanism embodying my invention mounted in a dental handpiece like that described in Letters Patent of the 60 United States No. 522,291, issued to me July 3, 1894, which comprises a handpiece provided with a collar capable of rotating thereon in a plane at an oblique angle to the axis of the handpiece and having mounted thereon an 65 elbow-shaped head carrying a tool-holder, whereby the axis of the tool-holder may be placed at varying angles to the axis of the handpiece.

Referring to the accompanying drawings, 70 A denotes the outer casing of the handpiece, provided with a tubular sleeve A', having a groove at its end in which is held a rotating collar A'', capable of turning in the groove with its axis at an oblique angle to the axis 75 of the handpiece and having an external screw-thread upon which is screwed a rotating elbow-shaped head B, carrying a tool-holder B' with its axis arranged at right angles to the axis of rotation of the head B and capable 80 of a slight longitudinal reciprocating motion.

The tool-holder B' is provided with an elongated mortise B'', adapted to receive the tip C' of an actuating-spindle C, held concentrically in the closed end of the sleeve A' and 85 capable of a sliding motion. The opposite end of the spindle C is provided with a blunt point C'', bearing against the beveled end D' of a reciprocating plunger D, which is attached at its opposite end by a pin D'' to a 90 tube E, capable of sliding in the casing A. The sliding tube E and plunger D are forced toward the spindle C by means of a spiral spring F, having one of its ends bearing against a plug E', screwed into the end of the 95 sliding tube E and having its opposite end bearing against the adjustable collar F', held upon the screw-threaded hub G' of a plug G, by which the end of the casing A is closed. An opening F'' in the casing A is provided to 100 allow the collar F' to be adjusted on the hub G' in order to vary the force of the spring F.

The sliding tube E is drawn back against the tension of the spiral spring F by means of a rotating cam H, acting against a cam-surface H' upon the plug E'. The cam H is carried upon a shaft H², having a spline connection with a cam H³, which is engaged by a cam H⁴, attached to a rotating shaft H⁵ in alinement with the shaft H² and journaled in the plug G and operatively connected by a coupling H⁶ with a flexible driving-shaft in the usual manner.

The cams H³ and H⁴ are inclosed in a shell I, which contains a spiral spring I', by which the cam H³ is held normally in engagement with the driving-cam H⁴, causing the rotation of the shaft H⁵ in one direction to be communicated to the shaft H², while the rotation of the shaft H⁵ in the opposite direction will cause the cam H³ to slide on the shaft H² and against the tension of the spiral spring I', thereby disconnecting the shafts H⁵ and H² whenever the motion of the driving-shaft H⁵ is reversed.

When the shaft H² is rotated, its attached cam H, acting against the cam-surface H' causes the sliding tube E and plunger D to be drawn back, thereby compressing the spiral spring F until the shaft H⁵ has made one revolution, when the cam H suddenly releases the sleeve A' and plunger D, allowing the spiral spring F to force the plunger forward and impart a blow to the pointed end C² of the actuating-spindle C, thereby forcing the flattened tip C' into the mortise B² of the tool-holder. The flattened tip C' of the spindle C is formed by slabbing the opposite sides of the spindle C, so as to form a flat blade at the end of the spindle, and the width of the blade is reduced at its end to form a tongue C³ and form beveled edges C⁴ and C⁵ on opposite edges of the blade.

The tongue C³ is arranged to enter the mortise B² and hold the tool-holder from turning, while the beveled edges C⁴ and C⁵ are adapted to strike against the end walls B³ and B⁴ of the mortise B².

In case the tool-holder is pushed into the head, as when the straight tool is employed, with its end a bearing against the work, then the beveled edge C⁴, as the spindle C is pushed forward by the action of the plunger D, strikes against the end wall B³ of the mortise and imparts a blow to the plugging-tool in the direction of the arrow 1, Fig. 3; but in case a bent plugging-tool is employed then the pressure of the tip b of the tool against the work serves to draw the tool-holder out and bring the end wall B⁴ in position to be struck by the beveled edge C⁵ of the actuating-spindle, causing a blow to be imparted to the plugging-tool in the direction of the arrow 2, Fig. 6. The blow of the plunger D is therefore imparted to the tool-holder in either direction, according to the plugging-tool which is used and the direction of the pressure of the tip of the plugging-tool upon the work, the force of the blow

being always in a direction opposite to that of the pressure which is exerted upon the tip of the plugging-tool as it is held against the work by the operator.

As the plugging-tool is moved out or in by its pressure on the work the contact of the end walls of the mortise B² will act against the beveled edges of the spindle C to reverse the movement of the spindle. For example, as the tool is pushed in by a pressure on the tip a the end wall B³ will act on the beveled edge C⁴, and as the tool is drawn out by a pressure applied to the tip b the end wall B⁴ will act against the beveled edge C⁵, and in either case cause the spindle to be held against the end of the plunger.

In case a plugging-tool of the kind shown in Fig. 3 is employed with its tip held against the work the pressure of the tool upon the work will always be exerted to push the holder into the rotating head, while the force of the blow exerted by the plunger D would be exerted in the opposite direction to force the blow against the work; but if a plugging-tool of the kind shown in Fig. 6 be used the pressure of the tip of the plugging-tool against the work will always tend to draw the tool-holder out of the rotating head and cause the blow exerted by the plunger to be exerted in the opposite direction.

The actuating-spindle is held concentrically with the rotation of the head B around the end of the sleeve A', so that the rotation of the head is always around the axis of the spindle C, in whatever position the rotating head may be placed, and the pointed end C² of the spindle C will always be presented to the center of the beveled end of the plunger D.

I do not confine myself to the specific actuating mechanism for imparting a blow to the plunger D, as other well-known mechanisms now used for this purpose in dental pluggers may be employed.

My present invention relates particularly to that part of the mechanism which is employed in communicating a blow of the plunger D to the tool-holder carrying a plugging-tool, whereby without any change or adjustment of the actuating mechanism a blow may be imparted by the plunger to the tool-holder to either force it into or out of the head B, so that plugging-tools of the character represented in Figs. 3 and 6 may be employed indiscriminately without change in the actuating mechanism.

The rotating collar A² is cut apart on one side and is sprung into a groove formed in the end of the sleeve A', the construction being substantially like that shown in United States Patent No. 522,291, above referred to. The screw-threaded collar is provided on one of its edges with a notch A³, by which the collar may be dogged and held from rotating while the head B is being screwed on or off.

I provide the sleeve A' with a longitudinal groove J deep enough to disclose the edge of

the rotating ring A², and within the groove J, I place a blade-spring J', having its end curved at J³ and bearing against the bottom of the groove J. The opposite edge of the blade-spring J' is attached to a sliding collar J². The bent end J³ of the blade-spring is adapted to engage the notch A³ by sliding the ring J² toward the head B and hold the collar from rotating.

5 When it is desired to release the collar A², the sliding collar J² is drawn back against the end of the outer casing A and is held in place by the pressure of the bent end of the blade-spring J' against the bottom of the groove.

15 What I claim as my invention, and desire to secure by Letters Patent, is—

1. The combination of a tool-holder provided with a recess presenting opposing walls 20 to the action of an actuating-spindle, a reciprocating plunger and an intermediate actuating-spindle provided with oppositely-beveled edges arranged to receive the blow of said plunger and engage the recessed tool-holder, whereby the blow of said plunger is imparted to said tool-holder in either of two opposite directions, substantially as described.

2. The combination of a tool-holder provided with a recess or mortise, an actuating-spindle provided with a tongue on one end entering said recess or mortise, and having oppositely-beveled edges arranged to contact with the walls of said recess or mortise, and means for imparting a blow against the opposite end of said actuating-spindle, substantially as described.

3. The combination with a dental hand-piece of a rotating head journaled on said handpiece, a reciprocating tool-holder held 40 in said head, with its axis at right angles to the axis of rotation of said head, a reciprocating plunger contained in said handpiece, means for imparting a blow to said plunger, an intermediate actuating-spindle between 45 said plunger and said tool-holder with its axis coincident with the axis of rotation of said head, said intermediate spindle being ar-

ranged to impart the blow received by said plunger to said tool-holder, substantially as described.

4. The combination of a reciprocating tool-holder having a transverse recess, or mortise, an actuating-spindle provided with a tongue entering said recess, and having oppositely-beveled surfaces arranged to engage the walls 55 of said recess, or mortise, whereby a longitudinal movement of said spindle will impart a longitudinal movement to said tool-holder, a reciprocating plunger arranged to impart a blow to said spindle, a spring arranged to 60 force said plunger against said spindle and means for compressing and releasing said spring, substantially as described.

5. The combination of plunger D, means for actuating said plunger, tool-holder B having 65 a mortise B², spindle C having one end in contact with the end of said plunger, tongue C³ entering said mortise, beveled edges C⁴ and C⁵ arranged to engage the walls of said mortise and convey the blow of said plunger to 70 said tool-holder in either direction, substantially as described.

6. In a dental plunger, the combination of a tool-holder, a spindle at right angles to said tool-holder and having a beveled surface at 75 one end of said spindle to engage said tool-holder and impart a longitudinal motion to said tool-holder, a reciprocating plunger by which a blow is given to the opposite end of said spindle and means for actuating said 80 plunger, substantially as described.

7. The combination with a handpiece provided with a groove J, of screw-threaded rotating collar provided with a notch A³, a head carried upon said collar, a blade-spring sliding in said groove and having its end adapted to engage the notch in said collar and means for sliding said blade-spring, substantially as described.

Dated this 26th day of July, 1899.
